(57) **CLAIM**

I claim the ornamental design for a forklift truck, as shown and described.

DESCRIPTION

Figure 1.1 is a front left perspective view of a forklift truck; Figure 1.2 is a rear right perspective view of the forklift truck of Figure 1.1;

Figure 1.3 is a rear view of the forklift truck of Figure 1.1;

Figure 1.4 is a front view of the forklift truck of Figure 1.1;

Figure 1.5 is a right side view of the forklift truck of Figure 1.1;

Figure 1.6 is a top view of the forklift truck of Figure 1.1; Figure 1.7 is a front right perspective view of the forklift truck of Figure 1.1;

Figure 1.8 is a left side view of the forklift truck of Figure 1.1; and

Figure 1.9 is a rear left perspective view of the forklift truck of Figure 1.1.
